(57) **CLAIM**

The ornamental design for an information handling system as shown and described.

DESCRIPTION

FIG. 1 is a front perspective view of the information handling system comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof;
FIG. 7 is a bottom view thereof;
FIG. 8 is a bottom perspective view thereof;
FIG. 9 is an enlarged view of portion '9' of the information handling system indicated by the detail box in FIG. 1; and, FIG. 10 is an enlarged view of portion '10' of the information handling system indicated by the detail box in FIG. 8. The broken line boxes in FIGS. 1 and 8-10 represent the extents of the enlarged detail views and form no part of the claimed design. All remaining broken lines illustrate portions of the information handling system that form no part of the claimed design.
